(57) **CLAIM**

We claim the ornamental design for latch housing with pivotal handle, as shown and described.

DESCRIPTION

Reference is made to design application Ser. No. 29/148,346, filed Sep. 18, 2001 by Lee S. Weinerman and Scott A. Arthurs entitled Front Portions of Latch Housing with Pivotal Handle which relates to "front portions" of the latch housing with pivotal handle embodiments that are the subject of the present application. The disclosure of said referenced application is incorporated herein by reference.

FIG. 1 is a perspective view showing front, left side and right end portions of one form of latch housing with pivotal handle embodying our new design;

FIG. 2 is a perspective view showing front, right side and left end portions thereof;

FIG. 3 is a top plan view thereof;

FIG. 4 is a right end elevational view thereof;

FIG. 5 is a bottom plan view thereof;

FIG. 6 is a left end elevational view thereof;

FIG. 7 is a right side elevational view thereof;

FIG. 8 is a left side elevational view thereof;

FIG. 9 is a perspective view showing front, left side and right end portions of another form of latch housing with pivotal handle embodying our new design;

FIG. 10 is a perspective view showing front, right side and left end portions thereof;

FIG. 11 is a top plan view thereof;

FIG. 12 is a right end elevational view thereof;

FIG. 13 is a bottom plan view thereof;

FIG. 14 is a left end elevational view thereof;

FIG. 15 is a right side elevational view thereof; and,

FIG. 16 is a left side elevational view thereof.
